UNITED STATES PATENT OFFICE.

JAMES W. COLEMAN, OF MONTREAL, QUEBEC, CANADA.

END CONSTRUCTION FOR CARS.

Application filed November 27, 1923. Serial No. 677,266.

To all whom it may concern:

Be it known that I, JAMES W. COLEMAN, a citizen of the United States of America, and resident of the city of Montreal, in the

5 Province of Quebec and Dominion of Canada, have invented certain new and useful Improvements in End Construction for Cars, of which the following is a full, clear, and exact description.

10 This invention relates to improvements in car end construction, and the primary object of the invention is to provide an end construction that will be proof against bulging due to end thrust of a load within the car.

15 A further object is the provision of end construction applicable equally to cars in course of building or as a repair to existing cars of either outside metal or wood frame construction.

20 A still further object is to provide a trussed end construction adapted to utilize the entire distance between the inner and outer surfaces of the end for truss depth, thereby ensuring requisite strength and 25 stiffness without undue weight of material.

Another object is to provide a trussed end construction or end reinforcement of maximum depth which will not encroach on the internal dimensions of the car nor produce 30 undesirable projections from the inner surface of the end.

Another object is the provision of a composite end construction in which stiffening members combine with planking to produce a complete end closure.

Still another object is the provision of an end construction of moderate cost and durable character which may be easily applied either in the construction of new cars or as 40 a repair with great ease and rapidity.

An additional object is the provision of a trussed end construction in which compression and tension members are formed integral and are, therefore, permanently in 45 proper relation and without possibility of slackening which would impair the efficiency of the truss.

Various other objects and advantages may be ascertained from the following description 50 and from the accompanying drawings.

In the drawings which illustrate but one

embodiment of the invention and without confining the invention to any detail or combination of details:—

Fig. 1 is an elevation of the improved end 55 construction from the floor line upward to nearly the roof.

Fig. 2 is a cross section on the line 2—2 of Figure 1 on an enlarged scale.

Fig. 3 is a partial vertical section at the 60 center, on the scale of Figure 2.

Fig. 4 is a view similar to Figure 2 showing supplementary sheathing.

Fig. 5 is an isometric view of a part of a 65 plate embodying the improved construction.

Referring more particularly to the drawings, 11 designates the corner posts or angles and 12 the intermediate uprights, usually Z-bars, of the outside metal frame of a car. As seen in end elevation the space between these uprights is occupied by alternately arranged compression members 13 and tension members 14 in any desired spacing, the compression members being arranged inwardly of the uprights and the 70 tension members outwardly of the intermediate uprights and inwardly of the corner uprights. In rear of the tension members and inwardly of the uprights the spaces between the compression members are filled in by 75 planking 15 or other suitable sheathing which combines with the compression members to form a complete end closure. The compression and tension members are, according to this invention, formed integral from a single sheet of metal by suitably upsetting and shearing the same to separate the members through the greater part of their length while leaving them integrally connected adjacent the ends. The sheet may be of any 80 suitable size, that is to say, a single sheet may suffice to form the entire truss construction of the car end in one piece or any suitable number of sheets may be employed.

The latter condition has been illustrated in 85 Figure 1 in which three sheets are illustrated, the lines of jointure between them being designated 16. The intermediate uprights 12 are interposed between the compression and tension members and serve as 90 queen posts or struts of the truss construction. 95

The compression members may be of any suitable cross section and are therefore not confined to the cross section illustrated. In the cross section illustrated each compression member comprises sides 17 preferably of uniform depth for a length equal to the distance between the rear outer edges of the uprights 12 with which the plate is to be assembled and tapering from this central portion toward the ends, as clearly shown in Figure 5. The tapering of the sides is preferably effected all in the innermost edge, thus leaving the outer edge, which is presented to the uprights, straight. The sides are connected by an integral web 18 disposed at the inner or inclined edges, with the result that this web is cambered or arched inwardly. Between adjacent compression members the plate is sheared in its central part in two preferably parallel lines located a short distance from the compression member sides so as to form outwardly turned flanges 19 at the sides of the compression member, which flanges provide adequate bearing surface for engagement with the intermediate uprights. The strip of metal thus partially severed from the plate between each pair of compression members forms a tension member, and this strip of metal is pressed in its central part outwardly of the line of the plate, that is to say, on the opposite side of the plate to the compression members. Each tension member presents preferably a central portion disposed in a plane parallel with that of the plate and having a length substantially equal to the distance between the outermost edges of the uprights 12 with which the plate is to be assembled. The end portions of the tension members slope from this central portion to the plane of the plate. In the pressing of the plate to produce the compression and tension members, inwardly extending flanges 20 are formed at the vertical edges of the plate disposed normal to the plane of the plate. The channels of the compression members preferably extend the entire distance between these flanges as shown, but the shearing to separate the compression and tension members preferably stops some distance from the flanges, the distance being preferably that equal to the leg length of the corner angle, so that when the plate is in position the edges of the angles will be located at or slightly inside the ends of the cuts in order to support the tension members and hold the plate against tearing at the ends of the cuts.

A single plate, or any suitable number of plates thus formed, are assembled with the uprights, as already described, the intermediate uprights passing tightly between the compression and tension members to complete the truss construction and properly tension the members. It will be observed

that the compression members are disposed concave sides out. The depth of these members over the webs and flanges is equal to the thickness of the end sheathing and therefore when the sheathing is in place between the members the inner surface is smooth and unbroken by any projections. Slight depressions are, however, formed adjacent the sides of the car between the zones or bands of sheathing, due to the camber of the compression members. These depressions are not objectionable providing the edges of the sheathing are chamfered as shown at 21, Figure 3, to avoid lodgment of material such as grain and also splintering. The edges of the sheathing are rabbeted at 22 to receive the flanges 19 of the compression members and are supported between the uprights, against outward pressure, by the flanges, so that the load on the sheathing is transmitted directly to the transverse trusses. The stiffeners are secured in place by bolts or the like 23 passing through the feet 20 and side legs of the corner uprights. In this way the sides of the car are tied together. The bolts may be the ordinary attaching bolts of the side sheathing or may be specially provided bolts.

In climates where exposure of metal on the inside of the car is undesirable on account of sweating or frosting, thin supplementary sheathing 24 may be provided internally or externally, or both.

When the car end is subjected to load as by the shifting of the contents due to inertia in stopping or starting the car, the pressure is partly sustained directly by the compression members and the remainder of the pressure which is against the sheathing is transmitted by the sheathing to the compression members. These members being arched or cambered tend to straighten out with consequent elongation, which tendency is resisted by the tension members in the well known manner. Owing to the continuity of the intermediate uprights through the entire truss construction, pressure localized at any level is distributed through the uprights to all tension members and to the corner uprights. The outward thrust against the end structure is transmitted through the corner uprights to the side frames of the car and at the same time the transverse truss construction positively ties the sides together against separation laterally from the ends.

The formation and disposition of the truss construction with the compression members thereof occupying the thickness of the end sheathing enables the entire space between the inner and outer surfaces of the end to be utilized. As the strength of the structure varies as the square of its depth, it will be readily seen that by utilizing the thickness of the end sheathing in addition to the available space outside the end of the truss

construction may be much stronger than would otherwise be possible unless by employment of much greater weight of metal.

While the structure has been described as of integral formation it will be understood that the invention also contemplates the employment of separately formed compression and tension members connected, as by riveting or welding, to vertical end members constituting the feet 20. Furthermore, while the structure is primarily intended to form with the sheathing a complete car end, it will be understood that a part only of the end may be thus formed. When the trussed end structure is applied as a repair to cars not having the intermediate uprights 12, for example a wood frame car, it will be necessary to provide the upright strut members 12. The compression and tension may also be disposed vertically and the members 12 horizontally.

Having thus described my invention, what I claim is:—

1. A car end comprising a series of integrally formed trusses, sheathing interposed between said trusses and forming with the trusses a complete end closure.

2. A car end comprising a series of connected transverse trusses including spaced compression members, end sheathing between said members, the sheathing and members forming a complete end closure, and tension members alternated with the compression members and connected at their ends to the ends of the compression members.

3. A car end comprising a plate sheared transversely in its central portion to provide parallel members connected at their ends by vertical unsheared portions of the plate, alternate portions being formed as compression members and the remaining portions as tension members, and a strut disposed between the tension and compression members, and sheathing disposed between the compression members and in the plane thereof.

4. A car end comprising a plate flanged at its ends and sheared in transverse lines terminating inwardly of the flanges, alternate portions of the plate between said shear lines being pressed to one side of the plane of the plate to form compression members and the remaining portions of the plate being pressed to the other side of the plane of the plate to form tension members, car end uprights passing between the compression and tension members and serving as truss struts and car end corner uprights connected to the plate flanges and overlying the unsheared end portions of the plate and holding the same against extension of the sheared lines by tearing when under load, and sheathing disposed between the compression members and in the plane thereof.

5. A car end comprising, in combination with corner and intermediate uprights and sheathing disposed inwardly of said uprights, a trussed reinforcing member including a series of transverse compression members arranged in spaced relation in the plane of the sheathing, and tension members disposed opposite the spaces between the compression members and outwardly of the intermediate uprights and inwardly of the corner uprights, said tension members being connected at their ends to the ends of adjoining compression members, the intermediate uprights serving as struts in the truss.

6. A car end including spaced transverse compression members and sheathing members alternated in a single plane, flanges on the compression members supporting the edges of the sheathing members and tension members disposed outwardly of the plane of the compression members, opposite the sheathing members and connected at their ends to the ends of adjoining compression members, and car end uprights interposed between the compression and tension members and serving as struts of the truss construction.

7. A car end including spaced transverse compression members, sheathing between the compression members and located in the same plane as the compression members, tension members alternated with the compression members and connected at their ends to the ends of adjoining compression members, said compression and tension members being cambered away from one another, and uprights disposed between the compression and tension members and tensioning all members to constitute a truss.

8. A device for use in car end construction comprising a plate flanged at opposite edges and sheared in spaced substantially parallel lines at right angles to the flanges to form a series of elongated portions separated at their side edges, alternate portions of the series being pressed to one side of the plane of the plate to present channel shaped members including flanged sides tapering toward the ends and cambered webs connecting the sides, the remaining plate portions being pressed to the opposite side of the plane of the plate and including end portions inclining to the plane of the plate.

9. A structure for use in car end construction comprising compression and tension members alternately arranged, and members traversing the ends of compression and tension members and connecting them together, the central parts of said compression and tension members being disposed in spaced planes to permit insertion of a strut member common to all the compression and tension members.

10. A structure according to claim 9, in

which the compression and tension and connecting members are formed integral from a single sheet of metal.

11. A car end comprising a series of trusses, each including integrally formed compression and tension members, and sheathing interposed between said trusses and forming with the trusses a complete end closure.
12. A car end comprising a series of trusses connected together at their ends, the compression and tension members of said trusses being arranged out of register whereby the compression and tension members are alternated in the plane of the car end and each compression member co-operates with adjacent tension members on each side thereof and each tension member co-operates with adjacent compression members on each side thereof, and sheathing interposed between

alternate truss members and forming with the truss members a complete end closure.

13. A car end comprising a series of trusses connected together at their ends, the compression and tension members of said trusses being arranged out of register whereby the compression and tension members are alternated in the plane of the car end and each compression member co-operates with adjacent tension members on each side thereof and each tension member co-operates with adjacent compression members on each side thereof, and sheathing interposed between the compression members of said trusses forming therewith a complete end closure, and strut members extending at right angles to the trusses.

In witness whereof, I have hereunto set my hand.

JAMES W. COLEMAN.
